(57) **CLAIM**

The ornamental design for a window box, as shown and described.

DESCRIPTION

FIG. 1 is a perspective view of the upper part of a window box shown from the side and below for convenience of illustration;

FIG. 2 is a perspective view of the lower part of a window box shown from the side and above for convenience of illustration;

FIG. 3 is a top plan view of FIG. 1;

FIG. 4 is a bottom plan view of FIG. 1;

FIG. 5 is a front elevational view of FIG. 1 it being understood that the opposite side is a mirror image thereof;

FIG. 6 is a side elevational view of FIG. 1 it being understood that the opposite side is a mirror image thereof;

FIG. 7 is a side elevational view of the combined upper and lower part of window box in assembled condition, it being understood that the opposite side is a mirror image thereof;

FIG. 8 is a top plan view of FIG. 2;

FIG. 9 is a bottom plan view of FIG. 2;

FIG. 10 is a side elevational view of FIG. 2;

FIG. 11 is a (side) cross-(cutting) sectional view taken along line 11—11 of FIG. 2;

FIG. 12 is a front elevational view of FIG. 2;

FIG. 13 is a (front) cross-(cutting) sectional view take along line 13—13 of FIG. 2;

FIG. 14 is a bottom view of the combined upper and lower parts of window box in assembled condition; and,

FIG. 15 is a front elevational view of the combined upper and lower parts of window box in assembled condition, it being understood that the opposite side is a mirror image thereof.

The broken line showing of environmental structure is for illustrative purposes only and forms no part of the claimed design.
